UNITED STATES PATENT OFFICE.

ROBERT M. HINRICH, OF DETROIT, MICHIGAN, ASSIGNOR TO DRAKE AVERY COMPANY, OF DETROIT, MICHIGAN, A CORPORATION OF MICHIGAN.

LOCK-TYPE-DAMPER REGULATOR.

Application filed April 11, 1927. Serial No. 182,898.

This invention relates generally to dampers for controlling the volume of air passing through heating and ventilating ducts and refers more particularly to locking means for dampers of the type specified.

In heating systems where the ordinary type of dampers are in use, it is of course readily apparent that any unauthorized person may tamper with and operate said damper. It has been found that where dampers are provided in heating systems used in schools, that the children will unintentionally tamper with the same and cause much inconvenience and unnecessary trouble. It is therefore one of the essential objects of the present invention to eliminate such objectionable features and provide dampers which are capable of being locked in their various positions of adjustment and which can be operated only by those persons having keys to fit such locking mechanism.

It is another object of this invention to enclose the locking mechanism in a tamper proof casing, but to provide means for indicating at all times the different positions to which the damper has been moved.

With these and other objects in view, the invention resides in the novel features of construction and combination and arrangement of parts as more fully hereinafter set forth.

In the accompanying drawings:

Figure 1 is a section through a heating or ventilator duct showing the damper together with the locking means therefor;

Figure 2 is a front elevation of the locking means with a portion of the casing broken away.

Figure 3 is a section taken on line 3-3 of Figure 2;

Figure 4 is a detail of the key for actuating the locking mechanism.

Figure 5 is an end elevation of the key.

In the drawings wherein like characters of reference indicate like parts the numeral 1 designates an ordinary heating or ventilating duct having mounted therein a damper 2 which is carried by the transversely extending shaft 3. As shown, this shaft is journaled in opposite walls of the duct, having one end portion 4 provided with a transverse opening to accommodate a cotter pin 5 and having its other end terminating in a squared portion 6.

Secured to the outside of one of the walls 55 of the duct 1 is a casing 7 having inner and outer walls 8 and 9 connected by means of an annular wall 10. Suitably mounted within this casing is a toothed wheel 11 provided with a square opening 12 for receiving the 60 square end portion 6 of the shaft 3.

As shown, the inner wall 8 of the casing is provided with a circular opening 13 and the gear wheel 11 is provided with an annular shoulder 14 fitting within this opening 65 and tending to position the wheel centrally within the casing. It will of course be noted that the toothed wheel is provided with a raised portion 15 extending laterally outward from the teeth 16 and having a flat 70 face portion 15' arranged to fit against the inside surface of the outer casing wall 9.

As shown in Figure 4 there is provided a key 17 having the handle portion 18 and the shank 19 which is provided at one end 75 with teeth 20 of substantially the same pitch as the teeth of the wheel 11. The end portion of the shank 19 carrying the teeth 20 is also provided with a longitudinally extending recess 21 and the inner wall 8 of the casing is provided with a stud 22 projecting therefrom and arranged to engage the slot 21 so as to pivotally position the key with respect to the toothed wheel. 80

As will be noted the casing is provided 85 with an opening 23 so designed as to allow for the insertion of the key in the casing with the teeth 20 turned away from the toothed wheel. However, just as soon as the key 17 is inserted in the casing it may 90 be rotated upon the stud 22 so that the teeth 20 mesh with the teeth 16 and thereby rotate the gear wheel and damper a certain predetermined distance.

For retaining the toothed wheel and damper in different positions of adjustment there is provided a spring 24 having the arm portions 25 connected by means of the hump 26, this hump being adapted to engage the teeth 16 of the wheel for holding the same 100 stationary except when actuated by means of the key 17.

In order to indicate the position of the damper at all times the flat face 15' is provided with suitable indicia 27. As shown 105 there are four points marked O and S for indicating the open and shut positions of the damper and in addition there are six

intermediate points indicating steps between the complete open and closed positions. An opening 28 is provided in the outer wall of the casing registering with the peripheral 5 portions of the face 15' for presenting the different letters and numerals when the damper is moved to different positions. It will thus be seen that no one will be able to operate the damper without first inserting 10 a key through the opening 23 and then turning the same so that the teeth of the key mesh with the teeth 16 of the toothed wheel. The key may be rotated until the desired 15 position of the damper is obtained whereupon it may be easily removed by allowing the teeth 20 to register with the opening 23.

While it is believed that from the foregoing description, the nature and advantage of my invention will be readily understood, 20 I desire to have it understood that I do not limit myself to the specific construction shown and described and that such changes may be resorted to when desired as fall within the scope of the claims.

25 What I claim as my invention is:—

1. In combination, a flue, a damper pivotally mounted within said flue, and means for locking said damper in different positions of adjustment including a wheel 30 rotatable with said damper, and adapted to have its periphery engaged by a key for actuating said damper.

2. In combination, a flue, a damper pivotally mounted within said flue, and means 35 for locking said damper in different positions of adjustment including a toothed wheel movable with said damper, and adapted to have its teeth engaged by a key.

3. In combination, a flue, a damper, a 40 shaft for supporting said damper journaled in said flue, a toothed wheel secured to one

end of said shaft outside of said flue, and adapted to be actuated by a key.

4. In combination, a flue, a damper, a shaft for supporting said damper journaled in said flue, a casing secured exteriorly of said flue, and a toothed wheel within said casing and secured to said shaft, and said casing being provided with an opening 45 adapted to receive a key for actuating said toothed wheel.

5. In combination, a flue, a damper, a shaft for supporting said damper journaled in said flue, a casing secured exteriorly of said flue, a toothed wheel within said casing and secured to said shaft, a stud mounted within 55 the casing and spaced from said wheel and adapted to pivotally position a key provided with a tooth for meshing with the teeth of the toothed wheel to move said damper to different positions of adjustment.

6. In combination, a flue, a damper pivotally mounted within said flue, means for locking said damper in different positions of adjustment including a member movable 60 with said damper, and adapted to be actuated by a key and indicia upon said member for indicating the various positions of adjustment of the damper.

7. In combination, a flue, a damper, a shaft for supporting said damper journaled in said flue, a casing secured exteriorly of said flue and having an opening in its outer 70 wall, a key operated toothed wheel within said casing and secured to said shaft, and indicia upon said wheel adapted to register with said casing opening for indicating the various positions of adjustment of said damper.

75 In testimony whereof I affix my signature.

ROBERT M. HINRICH.
